(57) **CLAIM**

The ornamental design for a kiosk as shown and described.

DESCRIPTION

FIG. 1 is a perspective view of a kiosk showing our new design from a first viewing direction;

FIG. 2 is a perspective view of the kiosk of FIG. 1 from a second viewing direction;

FIG. 3 is a front elevation view of the kiosk of FIG. 1;

FIG. 4 is a back elevation view the kiosk of FIG. 1;

FIG. 5 is a top plan view of the kiosk of FIG. 1;

FIG. 6 is a bottom plan view of the kiosk of FIG. 1;

FIG. 7 is a right side view of the kiosk of FIG. 1; and,

FIG. 8 is a left side view of the kiosk of FIG. 1.

The broken lines shown in the drawings illustrate portions of the kiosk that form no part of the claimed design.
